Primary Examiner — Robin Webster(57) **CLAIM**

The ornamental design for a rolling lawn and garden sprinkler and sprayer, as shown and described.

DESCRIPTION

FIG. 1 is a side elevation view of a rolling lawn and garden sprinkler and sprayer showing my new design;

FIG. 2 is a top plan view thereof; and,

FIG. 3 is a bottom plan view thereof.

The broken line showing of structural lines is included for the purpose of illustrating non-claimed subject matter and forms no part of the claimed design.
